UNITED STATES PATENT OFFICE.

CHARLES WHITTAKER, OF CHICAGO, ILLINOIS.

FAUCET.

SPECIFICATION forming part of Letters Patent No. 267,734, dated November 21, 1882.

Application filed June 12, 1882. (No model.)

To all whom it may concern:

Be it known that I, CHARLES WHITTAKER, a citizen of the United States, residing at Chicago, in the county of Cook and State of Illinois, have invented certain new and useful Improvements in Faucets; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to improvements in two-way faucets, and pertains more especially, first, to the device by which the two valves are simultaneously operated as the handle is revolved; second, to the peculiar construction and relative arrangement of the valve-chamber, barrel, valve-stem, and handle, said handle being located at the discharge end of the barrel, and said stem communicating therefrom to said valve-chamber through said barrel, as shown.

My invention is further explained by reference to the accompanying drawings, in which—

Figure 1 represents a longitudinal section. Fig. 2 is a transverse section of the valve-chamber, the chamber in Fig. 1 being drawn 30 on line $\alpha\alpha$ of Fig. 2.

Like parts are represented by the same reference-letters in both views.

A is the handle.

B is the barrel.

35 C is the valve-stem.

D is the valve-chamber.

E is the outlet or spout.

F and G are the inlet-ports to the valve or water chamber, through one of which ports 40 hot water and through the other cold water is admitted to the chamber, as desired. The water thus admitted passes from the chamber

through the barrel B, around stem C, and out through spout E, as indicated.

J is a crank formed upon or attached to the 45 end of the valve-stem C.

K is a wrist-pin formed upon the end of said crank, and is adapted to describe a circle around said spindle as the handle is revolved. Both of the valve-rods L and M are loosely 50 attached to the wrist-pin K, whereby they are simultaneously operated and said inlet-ports simultaneously opened and closed or alternately opened and closed, as desired, by revolving said handle.

Thus it is obvious that by the peculiar relative arrangement of said valves to each other and the crank I am enabled by the action of a single crank, as it describes a circle, either toward the right or left, to admit either hot or 60 cold water separately, or both simultaneously, as well as to stop the admission of both hot and cold water.

Having thus described my invention, what I claim as new, and desire to secure by Letters 65 Patent, is—

1. In a hot-and-cold-water faucet, the combination, in a single water-chamber, of two valves with a single crank-pin adapted by the peculiar relative arrangement of said valves to 70 said crank-pin to be both simultaneously and alternately opened and closed by the rotation of said pin, substantially as and for the purpose specified.

2. The combination of chamber D, provided with ports F and G, stoppers H and I, rods L and M, crank-pin K, valve-stem C, and handle A, substantially as set forth.

In testimony whereof I affix my signature in presence of two witnesses.

CHARLES WHITTAKER.
